CLAIM

The ornamental design for an information display holder for telephone cord, as shown and described.

DESCRIPTION

FIG. 1 is a perspective view of the information display holder for telephone cord showing my new design:

FIG. 2 is a front view thereof, the rear being a mirror image; and,

FIG. 3 is a side view thereof the other side being a mirror image.

The telephone and cord in FIG. 1 and the message card in FIGS. 1, 2, and 3 are shown in broken lines for illustrative purposes only and form no part of the claimed design.
